LUBRICATING SYSTEM FOR SEWING MACHINES

Harold J. Le Vesconte, Western Springs, and
 Albert M. Schweda, Chicago, Ill., assignors to
 Union Special Machine Company, Chicago, Ill.
 a corporation of Illinois

Application November 16, 1935, Serial No. 50,088

2 Claims. (Cl. 112—256)

This invention relates to lubricating systems for sewing machines. More specifically, it has reference to lubricating systems especially adapted for "cup feed" sewing machines of the type disclosed in U. S. Patent No. 2,043,737, granted to Norman V. Christensen on June 9, 1936. In the machine of this patent, the feed and stitching instrumentalities at the exterior of a hollow casting with a sump for lubricating oil in its base, are operated through members confined to oscillation, reciprocation or combinations of these movements and extending with a close working fit through a side wall of the housing, by actuating mechanism completely enclosed within said housing, said members and the parts of said actuating mechanism being all disposed above the level of the oil in the sump.

In connection with a sewing machine characterized as above, we aim to provide a simple and reliable circulating system whereby the oil is elevated from the sump for continuous discharge in spray form upon all the moving parts within the casing.

A further object of our invention is to provide, in a circulatory system operative under the principle outlined, a pump with a plunger motivated solely by contact with a reciprocating part of the actuating mechanism.

In the drawings, Fig. I is a longitudinal sectional view of a cup feed sewing machine identical with that featured in the aforesaid patent; and

Fig. II is an end elevation looking from the right of Fig. I, with portions of the machine housing broken out to expose the parts at the interior.

As in the patent supra, the sewing machine herein illustrated has an upright hollow housing 1 in which the actuating mechanism 2 is enclosed, said housing being formed exteriorly at one end thereof with an integral lateral shelf-like extension 3 wherein is journaled a vertical shaft 4. To the upper end of the shaft 4 above the extension 3 is secured a feed wheel or cup 6 with which cooperates a similar feed cup 7 at the top of another vertical shaft 8 journaled in an upright bracket arm 9. This bracket arm 9 is secured to a transverse pin 10 having its ends rotatively engaged in the side walls of a bottom hollow 12 of the extension 3, so that during the operation of the machine, the feed cup 7 can move toward and away from the feed cup 6 as required and as permitted by a spring (not shown) which is influential upon the bracket arm and which tends to maintain said cup 7 yieldingly in

engagement with its companion. The shafts 4 and 8 are coordinated at their lower ends for rotation in unison by a pair of intermeshing driving gear wheels 13 and 14, the gear wheel 13 being accommodated in the hollow 12 and the gear 5 wheel 14 in a complementary hollow 15 at the base of the bracket arm 9. Intermittent motion is imparted to the shaft 4 of the cup 6 in one direction by a clutch device 16 whereof the operating disk 17 is oscillated, through a link 18, by a pend- 10 ant arm 19 at one end of a horizontal shaft 20 which extends with a close working fit into the interior of the housing 1 through an elongate bearing boss 21 on the end wall 22 of said housing. The horizontal shaft 20 receives oscil- 15 latory motion as a consequence of the connection of a ball arm 23 at its inner end with a vertical rod 25 reciprocated by an eccentric 26 on the main shaft of the machine designated 27. As shown, the main shaft 27 extends crosswise of 20 the housing 1 and passes to the exterior through suitable bearings 28, 29 in the front and rear walls 30, 31 of said housing. At its outer ends the main shaft 27 is provided with belt wheels 32, 33, either of which may be used for driving the ma- 25 chine.

The stitch forming instrumentalities of the machine include a reciprocating needle 35, a four-motion looper 36 and an oscillating spreader 37, all of which operate in a well known manner above the feed cups 6 and 7 to stitch together abutted edge margins of a number of fabric sections passed between said feed cups. The needle 35, looper 36 and spreader 37 are secured to members in the form of shafts or rods 38, 39 and 30 40 which extend with a close working fit through relatively long bushings 41, 42, 43 in the side wall 22 of the housing 1 into the upper part of the latter for actuation by the mechanism 2. The necessary longitudinal reciprocating movements 40 are imparted to the needle bar 38 through a link 44, by a crank 45 on the main shaft 27. The shaft 39 carrying the looper 36 is oscillated and longitudinally reciprocated as well. The means for effecting the oscillatory movements of the 45 shaft 39 include an eccentric 46 on the main shaft which, through a link 47, is coupled with a lateral ball arm 48 on the inner end of said shaft. The endwise movements of the looper shaft 39 are induced by another crank 49 on the 50 main shaft 27 coordinated through a horizontal link 50 with the lower end of a rocker arm 51 fulcrumed about a fixed transverse axis 52 within the housing 1, the upper end of said arm being in turn pivotally connected at 53 to a collar 55

54 on the looper bar. A third eccentric 55 on the main shaft 27 has its link 56 coupled at the upper end with a lateral ball arm 57 at the inner end of the rod or shaft 40 which carries the 5 spreader 37.

10 The base of the housing 1 is utilized as a sump for oil L which is maintained at the level indicated below the horizontal shaft 20 and which is employed to lubricate the mechanism 2 in a 10 manner presently explained.

15 The circulating system with which the present invention is more especially concerned, comprises a vertical plunger pump 58 whereof the inlet 59 is submerged in the oil L. To the discharge outlet 60 of the pump 58 is connected a tube 61 which extends up along the rear end wall 62 of the housing 1 and then horizontally of the top of the latter over the mechanism 2. The horizontal branch of the tube 61 is provided along its bottom side with a series of perforations 63 so that the pumped oil is discharged in divergent sprays to insure its reaching all the parts of the mechanism 2. As shown, the plunger 65 of the pump 58 is urged upward by a compression spring 25 66 and thus maintained in contact engagement with a rounded protuberance 67 at the bottom end of the eccentric rod 25, and is accordingly obliged to partake of the up and down movements of said rod.

30 Since the feed cup, needle, looper and spreader operating shafts 20, 38, 39 and 40 and all the moving parts of the mechanism 2 are above the level of the oil L, the latter is not agitated by them nor heated by friction generated in them.

35 The oil is thus safeguarded against injurious churning and heating incident to operation of the machine at high speeds and therefore maintained in good condition for a very much longer time than would otherwise be the case. Obviously, due to close fitment of the oscillating shafts 20, 38, 39 and 40 in the long bearings 21, 41, 42 and 43 and by virtue of the fact that they have only very limited oscillating or reciprocating movement, the oil cannot possibly escape 45 to the exterior of the casing to soil the work which is being sewed in the machine.

Having thus described our invention, we claim:

1. A lubricating system for a cup feed sewing machine having an upright housing, a pair of feed cups supported at an elevation, a needle and a looper above the feed cups respectively operated by members protruding through oil tight bearings in the front wall of the housing for actuation by mechanism completely enclosed within said housing, means for driving the feed cups from below, and a connection for the drive means also extending through an oil tight bearing in the front wall of the housing for actuation by the actuating mechanism, said system including an oil sump in the base of the housing below the level of the feed cup driving connection aforesaid, and reciprocatory pump means motivated solely by contact with the feed cup driving connection within the housing to elevate oil from the sump for spray distribution upon the parts of the actuating mechanism as well as upon those portions of the 20 needle and looper operating members and the feed cup driving connection within the housing.

2. A lubricating system for a cup feed sewing machine having an upright housing, a pair of feed cups supported at an elevation, a needle and a looper above the feed cups respectively operated by members protruding through oil tight bearings in the front wall of the housing for actuation by mechanism completely enclosed within said housing, means for driving the feed cups from below including a horizontal rock shaft extending inwards through an oil tight bearing in the front wall of the housing and an operating rod depending from the actuating mechanism and coordinated with a crank at the inner end of said rock shaft, said system comprising an oil sump in the base of the housing below the level of the rock shaft, and a pump with a spring pressed plunger actuated solely by contact with the operating rod aforesaid for elevating oil from the sump for 40 spray distribution upon the actuating mechanism as well as upon those portions of the needle and looper operating members and the rock shaft within the housing.
